UNITED STATES PATENT OFFICE.

WILLIAM W. McELRATH, JR., OF EAST RADFORD, VIRGINIA.

MUFFLER FOR INTERNAL-COMBUSTION ENGINES.

1,245,364.

Specification of Letters Patent.

Patented Nov. 6, 1917.

Application filed June 3, 1916. Serial No. 101,527.

To all whom it may concern:

Be it known that I, WILLIAM W. McELRATH, Jr., a citizen of the United States, residing at East Radford, in the county of 5 Montgomery and State of Virginia, have invented certain new and useful Improvements in Mufflers for Internal-Combustion Engines, of which the following is a specification, reference being had to the accompanying drawings.

This invention relates to an improved muffler for internal combustion engines, and has for its primary object to provide simple and effective means for muffling the 15 gases exhausted from the engine cylinders prior to their discharge into the atmosphere.

It is another object of my invention to provide a device for the above purpose, embodying a muffler wheel or rotor mounted 20 upon the crank shaft of the engine and inclosed within a water jacketed casing, said rotor having a series of peripheral pockets into which the gases are admitted for expansion and are delivered therefrom to an 25 exhaust port at substantially atmospheric pressure.

Another aim is to provide a gas turbine engine that will consist of few parts easy to build and assemble, reducing wear to a 30 minimum and cheap to construct and install.

To accomplish these various objects, the invention broadly stated comprises a rotor secured to a crank shaft, the rotor consisting of two sections, the peripheral edge of 35 which has pockets formed therein, a casing or housing including a water jacket, ports for the ingress and egress of the water, and ports for the ingress and egress of the exhaust gases to the rotor, said rotor being 40 positioned between the connecting rods of a reciprocating gas engine and the said casing or housing being provided with means to form a bearing for the crank shaft.

One practical form and assembly of the 45 turbine is illustrated in the accompanying drawings, in which—

Figure 1 is a side elevation of the exhaust side of the reciprocating gas engine with the rotor and its casing in section;

50 Fig. 2 is a transverse section of the casing or housing showing the several ports and the water jacket;

Fig. 3 is a vertical section on the line 3—3 of Fig. 2;

55 Fig. 4 is a side elevation of the rotor; and

Fig. 5 is a sectional view of the rotor on the line 5—5 of Fig. 4.

The block for the gas engine cylinders, shown in Fig. 1 is designated by the letter A. The inlet manifold 6 connects with the two inlet valves indicated at 7 and 8. These inlet valves are provided with the usual valve stems 9 and 10. Disposed adjacent to these inlet valves 7 and 8 are the exhaust valves 11 and 12 which are also provided with valve stems 13 and 14. To maintain these several valve stems in their operative position, the yokes 15 and 16 are provided. These yokes may be secured to the block casting A in any suitable manner, one form 70 of which is shown by means of the stubs 17 and 18 and the nuts 19 and 20.

The water manifold for the heated water is indicated at 21 in Fig. 1, where it is shown communicating with the top of the 75 cylinders and the water jacket 22 therefor. The exhaust manifold, indicated at 23 is provided with the branches 24 and 25, as shown. To connect this exhaust manifold 23 with the crank case or housing, a suitable 80 flange 26 is provided, as shown and to secure this flange to the casing, the bolts 27 and 28 are employed.

The exhaust gases from the adjacent engine cylinders are admitted through the 85 pipe connection 29 to the exhaust manifold 23, to the housing or casing 30. The passage 31 is formed in the annular portion 32 of the casing, into which the gases are admitted from the pipe 29. This annular portion 32 90 of the casing is preferably provided in its inner surface with spaced recesses 33 forming expansion chambers into which the gas enters through the ports 34, said ports gradually flaring from their inner ends to 95 the periphery of the portion 32 of the casing. The casing is provided with a water jacket, indicated at 35, formed between the outer casing wall and an inner spaced wall 36. This water jacket practically entirely surrounds the passage 31.

The gases entering from the manifold 23, passing into the gas space 31 surrounding the nozzle carrying member 32 passes into the nozzles and striking the rotor are discharged after passing around in the casing a distance of more than 180° to the gas exhaust pipe 37. The water coming from the centrifugal pump (not shown) enters at the water inlet 38 and is adapted to pass in 110

either direction around the gas chamber 31 formed between the walls 30 and 36 to the water outlet 39 at the top of the casing or housing 30 as shown in Fig. 2. The water, 5 after leaving the turbine casing passes to the cylinder water jacket.

The walls 30 and 36, as shown in Fig. 3, curve inwardly toward each other. The walls are then extended inwardly and radially so as to form a solid member or web 40. 10 This web 40 is provided with a central aperture which is adapted to form a bearing when in coöperative relation with the flanges 41, as shown in Fig. 3. The webs 40 are spaced from each other in their vertical 15 planes so as to provide a space for the rotation of the web of the rotor therebetween.

The casing or housing 30 may be formed in two sections and these two sections may 20 be secured together in any suitable manner, as by means of the bolts 42. These bolts are shown in section in Fig. 2. The bolts 43 and the nuts 44 may also be used to hold the casing together if it should be divided in a different line.

The rotor is preferably circular in outline and may be formed into two parts or sections. The peripheral or rim portion of the rotor has pockets formed therein, as indicated at 45. These pockets are spaced from 30 each other and this spaced relation is shown more particularly in Fig. 2, where they are dotted in. The rim or peripheral portion of this rotor is disposed centrally upon a web 35 46 which is provided with a hub 47. Upon each side of the hub are disposed the flanges 41 which may be secured to the hub by means of the cap bolts 48, as shown. The two halves or portions of the rotor may be 40 secured together by means of the bolt 49 and the nuts 49^a passing through the bosses 50 and 51. The recesses adjacent the bosses permit the assembly of the two halves of the 45 rotor. This hub 47 may be secured to the shaft in any well known manner, one of which is indicated by the keys 52.

This web 46 may be provided with suitable apertures to reduce the weight of the rotor and yet not take away from its 50 strength or rigidity. To produce a true rotation around the crank shaft 53, suitable balancing means may be employed to position the rotor in a running balance, one means being shown by the apertures 54 formed in or near the peripheral edge of the 55 rotor.

In the operation of my invention, it will be understood that the exhaust gases are delivered from the engine cylinders through 60 the pipe connection 23 and the ports or nozzles 34 into the pockets 45 of the rotor. As

the rotor pockets successively pass the pockets 33 in the annular member 32, the gases expand, and when these gases are finally delivered through the exhaust 37, 65 they are at substantially atmospheric pressure so that there will be practically no noise incident to the exhaust of the gases to the atmosphere.

It will be understood that any desired 70 number of turbines may be employed, and as they are arranged between the connecting rods of the cylinder pistons upon the crank shaft, they will serve to materially reduce vibration in the operation of the engine. 75

Minor changes in form and details of construction may be resorted to without departing from the spirit of my invention or the scope of the appended claims.

Having described this invention, what is 80 claimed is:

1. A muffler for internal combustion engines including in combination with the engine having a crank shaft, a rotor fixed upon the engine shaft between the cranks thereof, 85 a relatively stationary annulus surrounding said rotor and provided with spaced pockets on its inner face and inlets thereto, said rotor being also provided with spaced pockets in its periphery in opposed relation to the 90 pockets in the annulus, and a casing surrounding the annulus and having a connection at one side of the rotor axis to the exhaust ports of the engine cylinders and provided at the opposite side of the rotor axis 95 with a port opening to the atmosphere.

2. A muffler for internal combustion engines including in combination with the engine having a crank shaft and case, a rotor fixed upon the engine shaft, a water jacketed 100 casing inclosing the rotor and mounted within the crank case of the engine, a relatively fixed annulus within said casing surrounding the rotor, the inner face of said annulus and the periphery of the rotor being 105 provided with spaced pockets, said annulus having inlet ports leading to the respective pockets from the outer face of the annulus, and a pipe connection between one side of 110 the casing and the exhaust ports of the engine cylinders to supply the exhaust gases to the pockets in said annulus, said gases expanding into the pockets of the rotor in the rotation thereof, and said casing being further provided with an outlet port for 115 the expanded gases open to the atmosphere.

In testimony whereof I hereunto affix my signature in the presence of two witnesses.

WILLIAM W. McELRATH, JR.
